(57) **CLAIM**

The ornamental design for a twisted bottle as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of an embodiment of a twisted bottle embodying our new design, wherein the color is disclaimed;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is perspective view of an embodiment of a twisted bottle embodying our new design;

FIG. 9 is a front view thereof;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a perspective view of the title twisted bottle, embodying the new design;

FIG. 16 is a front view thereof;

(Continued)

FIG. 17 is a back view thereof;
 FIG. 18 is a left view thereof;
 FIG. 19 is a right view thereof;
 FIG. 20 is a top view thereof;
 FIG. 21 is a bottom view thereof;
 FIG. 22 is a perspective view of the title twisted bottle, embodying the new design;
 FIG. 23 is a front view thereof;
 FIG. 24 is a back view thereof;
 FIG. 25 is a left view thereof;
 FIG. 26 is a right view thereof;
 FIG. 27 is a top view thereof;
 FIG. 28 is a bottom view thereof;
 FIG. 29 is a perspective view of the title twisted bottle, embodying the new design;
 FIG. 30 is a front view thereof;
 FIG. 31 is a back view thereof;
 FIG. 32 is a left view thereof;
 FIG. 33 is a right view thereof;
 FIG. 34 is a top view thereof;
 FIG. 35 is a bottom view thereof;
 FIG. 36 is a perspective view of the title twisted bottle, embodying the new design;
 FIG. 37 is a front view thereof;
 FIG. 38 is a back view thereof;
 FIG. 39 is a left view thereof;
 FIG. 40 is a right view thereof;
 FIG. 41 is a top view thereof;
 FIG. 42 is a bottom view thereof;
 FIG. 43 is a perspective view of the title twisted bottle, embodying the new design;
 FIG. 44 is a front view thereof;
 FIG. 45 is a back view thereof;
 FIG. 46 is a left view thereof;
 FIG. 47 is a right view thereof;
 FIG. 48 is a top view thereof;
 FIG. 49 is a bottom view thereof;
 FIG. 50 is a perspective view of the title twisted bottle, embodying the new design;
 FIG. 51 is a front view thereof;
 FIG. 52 is a back view thereof;
 FIG. 53 is a left view thereof;
 FIG. 54 is a right view thereof;
 FIG. 55 is a top view thereof;
 FIG. 56 is a bottom view thereof.
 FIG. 57 is a perspective view of an embodiment of a twisted bottle embodying our new design;
 FIG. 58 is a front view thereof;
 FIG. 59 is a back view thereof;
 FIG. 60 is a left view thereof;
 FIG. 61 is a right view thereof;
 FIG. 62 is a top view thereof;
 FIG. 63 is a bottom view thereof;
 FIG. 64 is a perspective view of an embodiment of a twisted bottle embodying our new design;
 FIG. 65 is a front view thereof;
 FIG. 66 is a back view thereof;
 FIG. 67 is a left view thereof;
 FIG. 68 is a right view thereof;
 FIG. 69 is a top view thereof;
 FIG. 70 is a bottom view thereof;
 FIG. 71 is a perspective view of an embodiment of a twisted bottle embodying our new design;
 FIG. 72 is a front view thereof;
 FIG. 73 is a back view thereof;

FIG. 74 is a left view thereof;
 FIG. 75 is a right view thereof;
 FIG. 76 is a top view thereof; and,
 FIG. 77 is a bottom view thereof.
 The broken lines illustrate structure or features that form no part of the claimed design.
